PONY CART OR THE LIKE

Byron T. Carrier, York Cemetery Road, Yorktown, Ind.

Filed Oct. 28, 1963, Ser. No. 77,184

Term of patent 14 years

(Cl. D14—3)

FIG. 1 is a perspective view of a pony cart or the like, showing my new design;

FIG. 2 is a side view of the cart; and

FIG. 3 is a rear view of the cart.

I claim:

The ornamental design for a pony cart or the like, as shown.
